CLAIM

The ornamental design for a skin treatment tip, as shown and described herein.

DESCRIPTION

FIG. 1 is a front perspective view of a skin treatment tip. FIG. 2 is a rear perspective view of the skin treatment tip of FIG. 1.

FIG. 3 is a front view of the skin treatment tip of FIG. 1. FIG. 4 is a rear view of the skin treatment tip of FIG. 1. FIG. 5 is a left side view of the skin treatment tip of FIG. 1. FIG. 6 is a right side view of the skin treatment tip of FIG. 1.

FIG. 7 is a top view of the skin treatment tip of FIG. 1; and, FIG. 8 is a bottom view of the skin treatment tip of FIG. 1.

1 Claim, 8 Drawing Sheets
